UNITED STATES PATENT OFFICE.

HENRY E. LEE, OF HUDSON, OHIO.

DESIGN FOR A BAG-HOLDER.

SPECIFICATION forming part of Design No. 33,955, dated January 22, 1901.

Application filed December 24, 1900. Serial No. 40,981. Term of patent 7 years.

To all whom it may concern:

Be it known that I, HENRY E. LEE, a citizen of the United States, residing at Hudson, in the county of Summit and State of Ohio, have 5 invented and produced a new and original Design for a Bag-Holder; and I do hereby declare the following to be a full, clear, and exact description of the same, reference being had to the accompanying drawings, forming a part thereof.

This invention relates to a novel and unique design for bag-holders for milling machinery and places where grain, feed, flour, and the like are sacked for the market.

15 The characteristic feature of the design is a body having three of its walls upwardly divergent and terminating in vertical portions and having the fourth wall vertical, a neck springing from the lower or smaller end of the 20 body and having its walls vertical and forming extensions of the walls of the body, the wall of the neck corresponding with the vertical wall of the body being in the plane thereof, and hooks applied to the outer sides 25 of the walls of the neck.

For a full disclosure of the design reference is to be had to the following description and the drawings hereto attached, in which—

Figure 1 is a perspective view of a bag- 30 holder formed on the lines of the design. Fig. 2 is a front view, and Fig. 3 a side view, thereof. Corresponding and like parts are referred

to in the following description and indicated in all the views of the drawings by the same reference characters.

35 The device comprises a body A and a neck B, each consisting of four walls or sides. The front wall 1 and the back wall 2 are of approximately triangular form, whereas the side walls 3 are of the form of tetragons. The 40 front and side walls are upwardly divergent and terminate in vertical extensions b. The back wall 2 is vertical, and its top edge terminates in the plane of the upper edges of the vertical extensions b.

45 The neck B is composed of four walls 4 of quadrangular shape and vertically disposed and is located at the lower or smaller end of the body. The back wall of the neck is in the plane of the back wall 2, and all the walls 50 merge into the corresponding walls of the body. The hooks 5 are applied to the outer sides of the walls 4.

Having thus described the invention, what 55 is claimed as new is—

The design for a bag-holder, substantially as herein shown and described.

In testimony whereof I affix my signature in presence of two witnesses.

HENRY E. LEE. [L. S.]
